UNITED STATES PATENT OFFICE

RUDOLF BÖMIG, OF RÖTHA/LEIPZIG, GERMANY

RAIL-BONDING MEANS

Application filed February 27, 1923, Serial No. 257,442, and in Poland January 3, 1927.

The invention relates to an improvement in electrical bonding means for the meeting ends of railway rails wherein, through the provision of certain mechanical elements, the electrical continuity of the railway rails is insured.

The main object of the present invention is the provision of clamps in the form of yokes and a contact plate held between the yoke and rail and furnishing a comparatively large contact surface between a conductor and the rail end, the yoke being moved to a position to securely hold the contact plate through the use of a wedge.

15 The invention is illustrated in the accompanying drawings, in which:

Figure 1 is a vertical sectional view through a railroad rail illustrating the improved bonding means in applied position.

20 Figure 2 is a side elevation showing the meeting ends to railroad rails and the bonding means applied to the respective ends of said rails.

Figure 3 is a detailed perspective view of 25 the wedge.

The invention is designed to provide means for electrically bonding the meeting ends of railroad rails *b* and includes a yoke member *a* adapted to underlie the base flange *b*₁ of the 30 rail, the ends of which are formed in return bends and to overlie the edges of the base flange. The yoke member is preferably in the form of a metallic plate and may if desired have longitudinally ranging spaced reinforcing or strengthening ribs *a*₁, whereby the yoke is in effect a rigid member.

That portion of the yoke overlying one edge of the base flange of the rail is of greater length than the opposite similar end of the 40 yoke and between such extended end and the base flange is arranged a contact plate *c* having a portion to overlie the upper surface of the base flange and a portion to abut squarely against the edge of the base flange. Thus 45 the contact plate *c* has a comparatively broad contact cooperation throughout the areas *c*₂, as indicated in Figure 1.

The relatively outer edge of the contact plate is formed more or less concave, as indicated at *c*₁, between which and the rounded

surface of the yoke end is arranged the conductor proper, indicated at *d*, which extends from one bonding means to the other across the meeting ends of the respective rails to be bonded. Between the opposite yoke end and the edge of the base flange of the rail there is interposed a wedge *e*, the outer edge *e*₂ of which conforms to the curvature of the adjacent end of the yoke and the inner edge *e*₁ of which is preferably formed with vertically ranging teeth serving to hold the wedge in applied position against displacement under the jar incident to the travel of the trains.

As applied, it will be seen that the wedge forces the yoke transversely with respect to the rail and not only binds the conductor *d* firmly and securely between the yoke end and contact plate but also binds the contact plate securely against the edge and upper surface of the base flange, thus providing at each 70 juncture the intimate metallic contact necessary to a proper electrical conductivity.

It will be noted that the upper surface of the contact plate *c* and the corresponding overlying portion of the yoke are inclined 75 with respect to the horizontal, so that as the yoke is drawn to position by driving the wedge inwardly, there is a wedging cooperation between the yoke and contact plate, tending to more firmly secure the parts in the 80 desired surface contact.

It is understood that a bonding means such as here illustrated is secured to the end of each of the meeting ends of railroad rails with the conductor *d* extending from one 85 bonding means to the other, as indicated in Figure 2. Obviously, the wedges of these respective bonding means may be readily driven in place and if repair or replacement is necessary, may be driven out of position to 90 thereby at once free the parts. No permanent means having direct or indirect connection with the rails themselves is necessary and thus the liability of breakage or difficulty in separation is entirely avoided by the improved bonding means.

The present wedge connection is also suitable for connecting main ground lines as well as for transversely connecting parallel tracks of government railways and the like, in order 100

to compensate for the different potentials of the track.

What is claimed to be new is:

1. A bonding means for railroad rails comprising a one piece yoke adapted to underlie the base flange of the rail and having return bend portions to overlie the base flange, a contact plate of angle form held between one of the base flanges and the return bend of the yoke, and confined against the top and edge portion of one of the flanges of the rail and one of the return bends of the yoke, a wedge arranged between the opposite edge of the base flange and the other return bend of the yoke, and a connector secured between the contact plate and the adjacent return bent portion of the yoke whereby the wedge locks the yoke, contact plate, and connector, to the rail.
- 20 2. A bonding means for railroad rails comprising a one piece yoke adapted to underlie the base flange of the rail and having return bend portions to overlie the base flange, a contact plate of angle form held between one of the base flanges and the return bend of the yoke, and confined against the top and edge portion of one of the flanges of the rail and one of the return bends of the yoke, a wedge arranged between the opposite edge of the base flange and the other return bend of the yoke, and a connector secured between the contact plate and the yoke, the contact plate and the adjacent return bent portion of yoke being formed for a wedging cooperation as the yoke is moved under the influence of the first mentioned wedge, whereby the wedge locks the yoke, contact plate, and connector, to the rail.
- 25 3. A bonding means for railroad rails comprising a one piece yoke adapted to underlie the base flange of the rail and having return bend portions to overlie the base flange, a contact plate of angle form held between one of the base flanges and the return bend of the yoke, and confined against the top and edge portion of one of the flanges of the rail and the return bend of the yoke, a wedge arranged between the edge of the base flange and the other return bend of the yoke, and a connector secured between the contact plate and the yoke, said wedge having its outer edge conforming to the yoke and its inner edge formed with a series of teeth for cooperation with the edge of the base flange.

55 In testimony whereof I affix my signature.

RUDOLF BÖMIG. [L. S.]
